UNITED STATES PATENT OFFICE

2,514,823

FLAME ARRESTER

Samuel H. Yost, Worthington, Ohio, assignor to
The Jeffrey Manufacturing Company, a corpora-
tion of Ohio

Application April 23, 1948, Serial No. 22,932

1 Claim. (Cl. 220—88)

1

This invention relates to a flame arrester, and an object of the invention is to provide a very simple improved device of the above mentioned type.

Other objects of the invention will appear hereinafter, the novel features and combinations being set forth in the appended claim.

In the accompanying drawing:

Fig. 1 is an elevational view of a controller to which a pair of my improved flame arresters have been attached; and

Fig. 2 is a detailed view, part in section and part in plan, showing the construction of said flame arresters.

Flame arresters are required in permissible equipment to prevent explosions when said equipment is used in gaseous coal mines. In connection with controllers or other spark producing equipment used with coal mining machines it is desirable to maintain a flow of air through the enclosed casing at all times so that the ionized air produced whenever a contact is open will not form sufficient nitrous acid which is allowed to form will seriously attack the copper, insulation and, in fact, many operating parts of the controller.

As illustrated in Fig. 1 of the drawings, the controller 10 is provided with a pair of flame arresters 11 of similar construction, one of which is connected to a flexible conduit 12 which derives a flow of air from a fan or blower, the air flowing through the flame arrester 11 and into the totally enclosed housing of the controller 10, thence out of said housing through the other flame arrester 11 at the left-hand side of said controller, as viewed in Fig. 1 of the drawing.

The flame arrester of my invention is very simple, yet it has been found entirely satisfactory and has been approved by the Bureau of Mines. It comprises essentially two main parts. Said two main parts are a cup 13 which has a nipple 14 thereon adjacent the center and bottom of the cup, which nipple is bored to provide a conduit 15 leading to the center and bottom of said cup. The cup has a generally cylindrical shape and of particular significance is the inner cylindrical surface 16 which extends for at least an inch and preferably slightly in excess of one inch; for example, it may extend 1½ inches.

Adjacent the right-hand edge of the cylindrical surface 16, as viewed in Fig. 2, the cup 13 is provided with a peripheral internal groove 17, adjacent and to the right of which it is threaded, as clearly illustrated in the drawing. The cup 13 receives a generally cylindrical plug 18 which

2

is a one-piece solid member and which has a continuous cylindrical external surface 19 generally coextensive with the cylindrical surface 16 and which is coextensive therewith for at least 1 inch and preferably slightly in excess thereof, such as 1½ inches.

The plug 18 is also preferably provided with a circumferential groove 20 which at least in part is opposite the groove 17, the two grooves 17 and 20 cooperating to form what is in effect a single circumferential groove or passageway around the external periphery of the plug 18 and the internal periphery of the cup 13. The bottom or left-hand end of the plug 18, as viewed in Fig. 2 of the drawing, is spaced slightly from the bottom of the cup 13, this spacing not being particularly critical, though preferably slightly in excess of the spacing between the surfaces 16 and 19. The spacing between the surfaces 16 and 19 is somewhat critical. It is preferably of the order of .020 inch.

Adjacent its right-hand end, as viewed in Fig. 2 of the drawing, and at its center the plug 18 is provided with a conduit-forming opening 21 which is preferably screw-threaded at 22 to receive a screw-threaded fitting whereby it may be attached to the housing 10 or the like. Opening 21 extends into a central axial conduit leading to the interior of the plug 18, from which there is a plurality of radial conduits 23 extending to the groove 20, thus providing branch passageways from the opening 21 to the peripheral groove 17—20.

The plug 18 is also provided with a peripheral ledge 24 and with threads to receive the threaded top of the cup 13. The ledge 24, of course determines the final position of the plug 18 with respect to the cup 13, thus positioning the bottom of the plug 18 from the bottom of the cup 13. If desired, a sealing wire 25 may lock the two principal parts of the arrester 11 together, and a similar sealing wire 26 may lock the arrester 11 to the housing 10.

As illustrated in Fig. 1 of the drawings, the two arresters 11 are connected to the housing 10 by virtue of fittings between said housing and the threaded openings 22. Air is fed to the nipple 14 of the right-hand flame arrester 11, the left-hand flame arrester having its conduit 15 in direct communication with the atmosphere. Air from a fan or blower is delivered by conduit 12 to the conduit or passageway 15 of the nipple 14 where it spreads through the area between the end of the plug 18 and the bottom of the cup 13, flowing radially outward

to a position where it can flow axially between the cylindrical surfaces 16 and 19, thence into the circumferential groove 17—20 from where it can freely flow from the radial bores 23 into the said opening 21 by way of the central conduit communicating therewith and with said bores 23.

Should an explosion take place within the enclosed controller box 10 the flames will be arrested or quenched before reaching atmosphere, since they will take a reverse path from that just described for the incoming air, the flame arresting taking place principally as the hot gases pass between the surfaces 16 and 19. Some arresting may take place between the end of the plug 18 and the bottom of the cup 13, but this path is not particularly relied upon for the flame arresting to function. Obviously, either flame or air can travel in either of the reverse directions through the flame arrester, and the function and operation will be the same in either case. As a matter of fact, the normal air flow will travel through the right-hand flame arrester 11 in one direction leading to the controller 10, and it will flow through the left-hand arrester 11 in a relatively reverse direction.

Obviously those skilled in the art may make various changes in the details and arrangement of parts without departing from the spirit and scope of the invention as defined by the claim 30 hereto appended, and I therefore wish not to be restricted to the precise construction herein disclosed.

Having thus described and shown an embodi-

ment of my invention, what I desire to secure by Letters Patent of the United States is:

A flame arrester for an electrical controller or the like comprising a two piece device including a cup having a cylindrical inner surface and a central conduit leading to the interior of said cup, a one-piece plug threaded into said cup having a continuous outer cylindrical wall near to but spaced slightly from said cylindrical inner surface and having opposite closely adjacent surfaces about .020 inch apart and extending for at least 1 inch along the axis of said cylindrical surfaces, and conduit means extending first into the center of said plug then radially thereof, said plug and cup cooperating to provide a circumferential groove adjacent the ends of said radial conduit portions and at the periphery of said plug, the end of said plug adjacent said first mentioned conduit being spaced from the bottom of said cup.
